UNITED STATES PATENT OFFICE.

RICHARD SAGER, OF MANNHEIM-RHEINAU, GERMANY, ASSIGNOR TO RHEINISCHE GUMMI- UND CELLULOID FABRIK, OF MANNHEIM-NECKARAU, GERMANY.

PACKING MEANS FOR COMBS TO PREVENT DISTORTION OF THE TEETH.

Application filed February 10, 1928, Serial No. 253,240, and in Germany May 20, 1927.

As is well known, the teeth of combs made from horn, rubber, artificial compositions and the like, especially the finer teeth, become easily distorted.

5 My present invention provides a packing means for such combs to prevent distortion of the teeth, said packing means consisting of a negative or counterpart comb (of inexpensive material, such as paste-board) the 10 teeth of which engage in the gaps between the comb teeth to be protected.

A constructional form of my invention is illustrated, by way of example, on the accompanying drawing, whereon:—

15 Fig. 1 shows a comb and a packing means for ensuring the form of its teeth, separated from one another; and

20 Fig. 2 is a fragmentary face view, to a larger scale, showing the comb and the packing means fitted together.

The packing means takes the form of a comb-like strip *c* having teeth *d* adapted to inter-engage with the teeth, or at least the finer teeth, of the comb *b*, said teeth *d* corresponding in width to the gaps between the finer teeth *a* of the comb *b*. Preferably the packing strip or counterpart comb *c* consists of paste-board or similar inexpensive material.

25 30 After the comb *b* is made and before it is despatched from the factory, the packing

strip *c* is brought into engagement therewith in the manner illustrated by Fig. 2, and the two members remain in this condition until the comb *b* is retailed, so that they 35 form in effect a single piece. The packing strip obviously protects the teeth of the comb with which it engages and prevents said teeth becoming distorted.

Having now fully described my invention, 40 what I claim and desire to secure by Letters Patent is:—

1. As a new article of manufacture a packing strip of cheap material in the form of a comb with short projecting teeth adapted 45 to be snugly wedged in between the tips of the teeth of a comb for the purpose of preventing the warping of the same out of parallelism one with another.

2. Packing means for preventing the distortion of the teeth of combs consisting of a counterpart comb of inexpensive material the teeth of which are of a thickness such as to completely fill the spaces between the ends of the teeth of the said comb when 55 inserted therebetween, whereby the warping of the teeth of said comb out of parallel one with another may be prevented when said counterpart comb is in position.

In testimony whereof I have affixed my 60 signature.

RICHARD SAGER.
